BRACELET END HOOK

August F. Kraemer, Providence, R. I., assignor to
Louis Stern Company, a corporation of Rhode
Island

Application April 10, 1934, Serial No. 719,882

4 Claims. (Cl. 24—265)

This invention relates to a connector for a bracelet commonly called an "end hook" for attaching the bracelet to the lugs of a wrist watch, and has for one of its objects the provision of means whereby the same may extend between the lugs of a wrist watch which are varying distances apart, and thus may be adjusted to varying sizes and eliminate the interchanging of end hooks which has been frequent in the trade to adapt the connector to the varying widths between the wrist watch lugs on different watches.

Another object of the invention is the provision of means for covering the pin on the watch which extends between the lugs which are varying distances apart so that the end hook will be adapted to different watches.

Another object of the invention is the provision of means which through resiliency will allow such adjustment of size to be affected and thus one which may be quickly and readily adapted to the size desired without the use of tools or the like.

Another object of the invention is the provision of a construction by which the pin extending between the lugs of the wrist watch is utilized rather than the attempting to provide some connector to replace the pin extending between the lugs, and which pin is furnished as a part of the watch.

With these and other objects in view, the invention consists of certain novel features of construction, as will be more fully described, and particularly pointed out in the appended claims.

In the accompanying drawing:

Fig. 1 is a top plan view of a wrist watch showing a bracelet attached thereto having ends embodying my invention.

Fig. 2 is a top plan view on a larger scale of the fragmental portion of a bracelet with my improved attaching end secured thereto.

Fig. 3 is a similar view looking at the bottom thereof.

Fig. 4 is a sectional view of the structure shown in Figures 2 and 3.

Fig. 5 is a section on line 5—5 of Figure 3.

Fig. 6 is a section on line 6—6 of Figure 2.

Fig. 7 is a top plan view of a modified construction.

Fig. 8 is a sectional view on line 8—8 of Figure 7.

Fig. 9 is a further modification illustrating the hook as connected to a link bracelet.

Fig. 10 is a sectional view of a still further modification of end hook.

55 In the art of attaching bracelets to a wrist

watch lug it is found that the distance between the lugs of different wrist watches varies, and in order that the end connection between the watch and the bracelet may fit the lugs, it has been customary to make end hooks of varying lengths and detach them from the bracelet and interchanging it with a hook of the desired dimension for the wrist watch. Other methods have been to provide connecting means to be substituted for the pin which is furnished with the wrist watch and extends between the lugs. Such means may be that which projects solid parts with reduced portions to extend into the openings in the lugs. These openings vary in size, and this method has not been entirely satisfactory; and further, the pins are not of the ornamental character desired. In some instances, attachments have been formed where the projecting parts are on a buckle or some other portion which is to receive hollow ends of a solid portion, but nowhere am I aware that there has been an arrangement which will receive the pin furnished with the wrist watch which is of a size to accurately fit between the lugs and to cover this pin by forming an ornamental portion which will extend the entire distance between the lugs of varying sizes; and I have accomplished this by providing tubular portions with a spring between them all housed in a tubular body so that the length of the body may be the minimum distance between lugs to be accommodated and the tubular body plus the extended tubular members may be the maximum distance between the lugs to be accommodated; and the following is a more detailed description of the present embodiment of this invention, illustrating the preferred means by which these advantageous results may be accomplished:

With reference to the drawing, 10 designates the wrist watch having lugs 11 extending outwardly therefrom with a pin 12 extending between these lugs which may or may not embody a spring arrangement for detachment from position. The bracelet to be attached to the watch is designated 14, and is provided with a connecting device which is commonly called an end hook and which I designate generally 15.

This end hook is illustrated as provided with a tubular body 16 having slots 17 on the under side thereof. Within this body I have provided extension members 18 which are slidably mounted and of a size to fit rather snugly therein and be guided thereby. Each of these members consists essentially of a tube which is provided with a pin 19 to extend into the slot 17 in the body and be lim- 50 55

ited in its movement by the length of the slot and the pin abutting the ends thereof.

The extension members 18 are forced outwardly by a spring 20 of a helical formation and held 5 under compression between the ends 21 of the tubes 18 so that it continually tends to force the tubes 18 outwardly regardless of the position which they assume relative to the body in which they are slidably mounted. The spring 20 is of 10 a helical formation providing a clear opening through the center thereof which aligns with the opening 22 in the members 18 and provides a central opening through all of these parts for the reception of the pin 12 which extends there- 15 through and into the lugs 11. This pin will bear in the bores 22 in the tubes 18 rather than on the spring, thus allowing the spring freedom of movement to actuate the tubes outwardly.

When the tubes are at their full extent outwardly, as shown in Figures 2, 3, and 4, the maximum distance between the lugs 11 will be provided for, and the pin 12 extending therebetween will be completely covered by these ornamental tubes 18. However, when the distance between 25 the lugs is of lesser extent, the tubes may be forced inwardly slightly or forced inwardly sufficiently to accommodate the lesser distance between the lugs and where the minimum distance of the lugs is encountered, the tubes will be completely housed within the body 16 so that they will not be visible at all and the body 16 will occupy the full space between the lugs. By this arrangement an end hook is provided which will be of universal application to the lugs of a wrist 30 watch or to some other like article to which it may be desired to attach it.

I have illustrated in Figures 1 to 8 the body 15 of the end hook as formed integral with the bracelet band 14 by rolling the same from the end of 40 the stock thereof, and when forming the end hook in this manner, I may slot the end of the band in the portion which is to be rolled and roll it about the end tubes with their projecting pins 18 and spring 20 at the time which it is formed into the tubular shape of the body 16, thus providing 45 a simple means of assembly.

In Figures 7 and 8 I have reversed the construction of the stop arrangement by providing a pin 25 in the body 16 of the end hook and a slot 26 50 in each of the tubular members, where otherwise the structures in Figures 7 and 8 are like the structures in the provision in Figures 1 to 6.

In Figure 10 I have illustrated the tubular body 16 as formed separate from the band designated 55 21 and soldered to it as at 28, by which arrangement I may provide a seamless tube, designated 29, if desired, and cut the slots therein for the pin 19.

In Figure 9 I have illustrated the body 16 as 60 provided with a loop 30 to which a connecting link

31 is attached to join it to the end link 32 of the bracelet, or any other suitable means may be provided for attaching this connector or end hook when used for connecting a bracelet to the part to which it is desired it should be detachably connected.

The foregoing description is directed solely towards the construction illustrated, but I desire it to be understood that I reserve the privilege of resorting to all the mechanical changes to which 10 the device is susceptible, the invention being defined and limited only by the terms of the appended claims.

I claim:

1. An end hook for a bracelet comprising a tubular body and a pair of tubular members slidably with reference to said body and located therein to extend the effective length thereof at each end thereof, resilient means having a center opening acting on said members to force them outwardly, and means for mounting said body and member on the end of a bracelet band, said body, member and spring having openings extending completely through the center thereof for the reception of the pin of wrist watch lugs or the like.

2. An end hook for a bracelet comprising a tubular body and a pair of tubular members slidably with reference to said body and located therein to extend the effective length thereof at each 30 end thereof, a coiled spring acting on said members to force them outwardly, cooperating means between said body and members to limit the outward movement of said members, and means for mounting said body and member on the end of a 35 bracelet band, said body, member and spring having an opening extending completely through the center thereof for the reception of the pin of wrist watch lugs or the like.

3. An end hook comprising an embracing body 40 member, similarly shaped members of a size to fit therein and slidably mounted with reference thereto, and resilient means acting on the ends of said slidably mounted members to move them outwardly from the body member, said body, member and spring having an opening extending completely through the center thereof for the reception of the pin of wrist watch lugs or the like.

4. An end hook comprising an embracing body 45 member, similarly shaped members of a size to fit therein and slidably mounted with reference thereto, and a coiled spring acting on the ends of said slidably mounted members to move them outwardly from the body member, said body, member and spring having an opening extending completely through the center thereof for the reception of the pin of wrist watch lugs or the like.

AUGUST F. KRAMER.
